UNITED STATES PATENT OFFICE.

WILLIE E. OGDEN AND GERALD N. SMITH, OF CLARKSBURG, WEST VIRGINIA.

INTERNAL-COMBUSTION ENGINE.

Application filed June 15, 1925. Serial No. 37,114.

To all whom it may concern:

Be it known that we, WILLIE E. OGDEN and GERALD N. SMITH, citizens of the United States, and residents of Clarksburg, county of Harrison, and State of West Virginia, have invented certain new and useful Improvements in Internal-Combustion Engines, of which the following is a specification.

10 This invention relates to internal combustion engines, a principal feature of which is to provide means whereby liquid or gaseous fuel engines of the type now generally in use may be rendered more efficient in operation, less troublesome in practice and capable of developing greater power with less expenditure of fuel.

15 A further object of the invention is to provide means whereby smoother operation of the motor may be obtained; such operation being accomplished by more perfect combustion of the fuel, thus resulting in the elimination of noise and vibration in the motor whereby to insure smoother operation of the vehicle with which it is associated.

20 These objects, together with others which will appear as the description proceeds, are accomplished by means of the construction and arrangement hereinafter detailed, reference being had to the accompanying drawing, in which:

25 Fig. 1 is a vertical sectional view taken through the upper part of an internal combustion engine constructed in accordance with the invention,

30 Fig. 2 is a similar view showing a slight modification in the head construction, and

35 Fig. 3 is a similar view illustrating a still further modified form of the invention.

40 Our invention relates particularly to the construction of the motor head and combustion chambers for the cylinders; the arrangement being such as to make possible a motor producing less vibration when in operation, which produces less carbon, which develops more speed and power and smoothness of operation, which remains cooler than has been possible in other types of motor and which may be operated at a great saving of fuel. These results are achieved by firing a pure gaseous explosive charge, unmixed with dead or expended gases properly above the piston in such manner that the peak explosion is somewhat gradual and does not occur until momentarily after the piston has received its initial impulse.

Furthermore, the invention contemplates the use of previously burned gases remaining in the combustion chamber not to augment the new explosive charge, but merely to act as a cushion when the peak explosion occurs, as it is essential in the accomplishment of the objects of the invention that a cushioning effect be obtained without materially affecting the compression, and without the admixture of expended or burned gases with the fresh charge. The objects are furthermore accomplished by igniting the first charge from a point substantially remote from the location of the fresh explosive charge, which causes a more gradual or extended expansion of gases and ignition of the peak or bulk charge only after the piston has started upon its power stroke.

45 Referring now to the drawing, 1 represents generally the cylinder of a conventional type of internal combustion engine, having slidably arranged therein the piston represented at 2. The head of the motor is indicated at 3, and sits down upon the cylinder in the usual well known manner. This head is water jacketed as at 4 directly over the combustion space or chamber. The explosive charges are led to the combustion chamber from the valve 5, operating in the usual manner, and a spark plug or other igniting device 6 is arranged at one side of the combustion chamber and substantially remote therefrom. In the present instance, this plug is arranged relatively close to the valve 5 which is disposed to one side of the cylinder head.

50 The wall 7 constituting the top of the combustion chamber 8 of the head is so shaped directly beyond the piston as to provide a recess or pocket 9, well above the main combustion chamber. This wall, after defining this pocket, is lowered so as to lie relatively close to the upper edge of the cylinder, forming therewith a passage 10 through which the explosive charges must flow in reaching the combustion chamber 8. This passage is small as compared with the chamber 8, and is in communication at its outer end with the valve 5 governing the flow of charges to the combustion chamber. The spark plug 6 is arranged at the outer end of the passage 10 remote from the chamber 8, and in the present instance is disposed directly above the valve 5.

55 Figs. 2 and 3 of the drawing disclose the same inventive idea as shown by Fig. 1, ex-

cept that variations in the formation and location of the wall 7 are made to more markedly define or locate the pocket 9. This pocket, in all instances comprises what 5 may be termed a "trap", within which dead or spent gases are confined and remain substantially inert.

The combustion charge for the cylinder is drawn in through the valve 5 in the usual 10 manner, upon travel of the piston 2 downwardly. This charge is then compressed as the piston moves upwardly, while the dead or spent gases are compressed within pocket or recess 9. It will be observed that the portion 15 11 of the wall 7 constitutes a throat which connects the larger portion of the combustion chamber with the passage 10, and when the piston 2 has reached the limit of its upward travel, the space between the 20 piston and the portion 11 practically separates the combustion chamber 8 from the passage 10. This causes the peak charge in the chamber 8 to be highly compressed, and the spent or dead gases in the pocket 9 will 25 likewise be under pressure. It is preferable that ignition take place just prior to the piston reaching its limit of upward travel. Immediately upon ignition taking place in the passage 10, the expansion caused by 30 such igniting gases will be reflected in the chamber 8 and pocket 9, so that upon ignition taking place in combustion chamber 8 a relatively higher degree of pressure is obtained than has heretofore been possible. 35 By reason of the delayed or gradual ignition of the peak charge in combustion chamber 8, the piston 2 will have passed its limit of upward travel and will have started upon its power stroke. The pure explosive 40 charge does not co-mingle with the spent gases, as the same remain separate and distinct. At the time of firing, the initial ignition takes place at the far end of the restricted passage immediately adjacent to 45 the spark plug. The ignition continues throughout the restricted passage, whereupon the "peak" charge is exploded, thus producing a blended or gradual firing of the compressed gases. The shock incident 50 to the explosion within the combustion chamber 8 is partially absorbed by the dead gases pocketed in the recesses 9 whereby knocking in the motor is obviated, while at the same time the power of the explosion, 55 is increased, due to high compression and the purity of the explosive charge due to the absence of dead gases therein.

By creating the explosion in this manner, 60 we are enabled to obtain greater power from expansion of the gas with a minimum of combustible mixture. This is due entirely to the manner of ignition as well as to the

absence of spent gases in the compressed charge. Therefore, we are enabled to materially reduce the size of the combustion chamber with a corresponding decreased quantity of gas expended, with an increased degree of explosive force per unit of gaseous charge employed.

It will be observed that the spark plug 6 70 is arranged directly in the water head and removed from the water jacketed portion thereof. This prevents any cooling effect upon the spark plug, and due to the high degree of heat in the same which obviously results in the operation of the motor, the 75 sparking device is kept free from carbon or the collection of other substances to hinder its proper functioning. By reason of the fact that none of the dead gases co-mingle with the incoming explosive charge, 80 carbonizing within the combustion chamber is nullified. Furthermore, by omitting a water jacket at the point of introduction 85 of the combustible charge to the combustion chamber, a high degree of heat is maintained in the walls immediately adjacent thereto, which heat is transmitted to the incoming combustible charge, whereby a more volatile mixture is produced.

While the foregoing is a description of the invention in its preferred embodiments, it is apparent that the structure is susceptible of variations, such for instance as a more complete isolation of the dead charges, 95 or variation in the shape, size and construction of the passage 10, without departing from the spirit of the invention.

Having thus described our invention we 100 claim:

1. In an internal combustion engine, a head having an explosion chamber, a pocket in said head beyond said explosion chamber for the retention of dead gases and closed on all except one side, said one side communicating with said explosion chamber, a restricted passage leading to said explosion chamber, and ignition means beyond said passage.

2. In an internal combustion engine, a head and an explosion chamber, a pocket formed in said head beyond said explosion chamber for entrapping and retaining dead gases and closed on all except one side, said one side at all times in communication with said explosion chamber, a restricted passage leading to said explosion chamber for the introduction of explosive mixture thereto, and ignition means beyond said passage and remote from the explosion chamber.

In testimony wherof we hereby affix our signatures.

WILLIE E. OGDEN.
GERALD N. SMITH.
